UNITED STATES PATENT OFFICE.

JOHN DAWSON JENNINGS, OF CHARLESTON, SOUTH CAROLINA.

BURIAL APPARATUS.

Application filed November 4, 1921. Serial No. 512,820.

To all whom it may concern:

Be it known that I, JOHN DAWSON JENNINGS, a citizen of the United States, and a resident of Charleston, in the county of 5 Charleston and State of South Carolina, have invented certain new and useful Improvements in Burial Apparatus, of which the following is a specification.

This invention relates to burial apparatus, 10 and more particularly to such an apparatus as is designed to receive the earth from a freshly dug grave and hold the same until such time as it is desired to refill the grave, at which time the apparatus functions to deposit said earth in the grave in substantially a unit mass.

One object of the invention is to provide an apparatus of this character which may be dismantled and folded into a compact form 20 so that it may be readily transported from place to place, and which may be assembled and placed in operative position with a minimum expenditure of time and labor.

A further object of the invention is the 25 provision of such an apparatus which will be simple in construction, certain and efficient in operation, and which may be easily operated by one person.

The invention consists of certain new and 30 improved features of construction and combination of parts which are fully described in the following specification and illustrated in the accompanying drawings, it being understood, however, that the invention is not limited to the modification therein shown but that such changes may be made in materials and in detail of construction as fairly fall within the scope of the appended claims.

40 In the accompanying drawings, in which like numerals designate like parts throughout,

Figure 1 is a rear elevation of the invention.

45 Figure 2 is a side elevation of the same.

Figure 3 is a front elevation of the same.

Figures 4 and 5 are detail views of the elevating supports.

50 Figures 6 and 7 are detail views of the roller construction.

Figure 8 is a perspective view of a shaft hanger.

Figure 9 is a perspective view of a support journal.

Figure 10 is a detail view of the crank 55 and ratchet wheel.

Figure 11 is a side elevation of a track section elevated above existing grave mounds.

The embodiment of the invention illustrated in the accompanying drawings, comprises an earth box or hopper provided with a plurality of pivoted supporting members. The hopper is preferably formed of a plurality of suitably formed sections indicated 60 in the drawings by the numerals 1, 2, 3, 4 and 5. The sections 1 and 2 co-operate to form the bottom of the hopper and may be provided on their under side with a plurality of angular staples 6 adjacent their coinciding edge 7. These staples are designed to receive a co-operating U-shaped bolt 8, as shown in Figure 1 which functions to secure the sections 1 and 2 together and retain them in the same plane. These sections 1 70 and 2 may be further provided with a plurality of staples 9 on their rear edges, said staples being designed to receive a bolt 10 which functions to retain the edges of the sections in alignment and to prevent any longitudinal displacement of said sections.

The sections 1 and 2 are shown further provided with angular staples 11 on their outside edges, which are designed to receive co-operating lugs 12, carried by the sections 3, 4 and 5 adjacent their corresponding edges, and function to retain the sections 3, 4 and 5, in planes perpendicular to the plane of sections 1 and 2. To further assist in retaining the sections 3, 4 and 5 in 85 their proper relative positions, additional fastening means may be provided such as pivoted hooks 13 and 14 carried by the side sections 4 and 5, and designed to engage co-operating pins 13^a and 14^a suitably positioned on the end section 3 and the bottom sections 1 and 2. If desired the sections 1, 2 and 3 may each be formed of two or more sections joined together by a plurality of 90 hinges 15.

The hopper is shown provided with a plurality of telescopic elevating supports or legs illustrated in detail in Figures 4 and 5. These legs comprise a plurality of spaced apart sections 16 and 17 which may be of 105 similar formation and provided with aligned apertures 18 and 19 adjacent either extremity. The members 16 and 17 may be

held in spaced relation by ties or braces 20, and within said space is shown a leg 21 provided with a plurality of apertures 22, any one of which may be placed in alignment 5 with apertures 19 in the sections 16 and 17 so that by inserting a suitable pin 23 through said aligned apertures a liner adjustment of the supporting members is obtained.

- 10 The elevating supports may be attached to the hopper by means of journal members 24, shown in detail in Figure 9, said members being secured to the under side of the body by any suitable means. Each journal member 15 is shown provided with an aperture 25, designed to co-operate with apertures 18 in the sections 16 and 17, to receive a suitable pin 26, said pin serving to pivotally secure the supporting members to the body.
- 20 The adjustable legs 21 are shown provided with a roller 27 on their lower extremities said roller being attached thereto in any suitable manner such as is shown in Figures 6 and 7. The rollers 27 are designed to engage 25 suitably positioned tracks 28 which may be of any desired form and material, said tracks and rollers being designed to reduce the force necessary to raise the apparatus to its discharging position which operation 30 will be hereinafter described.

On the outside edges of sections 1 and 2, shaft hangers 29 may be mounted, and designed to receive a removable shaft 30 shown extending transversely across the entire 35 hopper and adjacent its under side. The shaft 30 is shown provided with a ratchet wheel 31 secured thereto by a suitable key 32, said ratchet being so positioned as to co-operate with a pawl 33 pivotally mounted on 40 the outside face of section 5 rear its lower edge, said ratchet and pawl serving to retain the hopper by means to be hereinafter described, at any desired elevation. To rotate the shaft, a crank 34 may be provided 45 which is shown formed integral with the shaft, but if desired the shaft may be made detachable with respect thereto. The shaft 30 may be provided with any suitable means such as apertures positioned in operative relation 50 with respect to the pivoted elevating supports whereby flexible wires or ropes 35 may be secured thereto and subsequently attached to screw eyes 36 carried by the cleats 20 of the supporting members. From 55 this description it will be understood that by rotating the shaft 30, the wires or ropes 35, secured thereto will necessarily wind around the same, this action causing the lower extremities of the supporting members 60 to move inwardly along the track raising the hopper to the position shown in Figures 1, 2 and 3.

To prevent the hopper sliding forward during the elevation of the same, the bottom 65 thereof is shown provided with a plu-

rality of prongs or spikes 36 near its forward edge and extending beyond the same, which are designed to engage and enter the ground or sod, thus precluding the possibility of any slipping action between the 70 hopper and the ground.

In the event there are existing mounds in the cemetery that would interfere with the laying of the track section 28, suitable track supports 38 may be provided, which 75 are designed to be placed between the mounds 39 and at a height sufficient to elevate the track above said mounds. These supports may be made of any desired form, and as shown in Figure 11 may be triangular in shape, the apexes of said supports engaging suitably provided notches 39^a in the 80 underside of the track sections.

In operation, the apparatus having been assembled according to the above specification, the prongs 36 are forced into the earth immediately adjacent the edge of the proposed grave, the tracks laid, and the elevating supports of the hopper extended rearwardly to bring the hopper into a substantially horizontal position. The grave is then dug and the earth therefrom deposited in the hopper of the apparatus. After the 95 ceremonies, and at such time as it is desired to refill the grave the hopper is elevated to the position shown in the drawings, the front section 3 removed by unlatching the hocks 13, lifting it out by means of suitable handles 37 on the upper edge thereof, it being understood that the hopper is at the 100 required angle to cause the contents to slide bodily into the excavation.

Having thus described my invention what I claim as new is:—

1. A burial apparatus comprising a hopper, a gate at one end of said hopper and adapted to open, means at such end of the hopper for engaging the ground whereby to prevent such end of the hopper from sliding along the ground when its other end is lifted, and means for holding the other end of the hopper elevated as and for the purpose set forth.

2. A burial apparatus comprising a hopper, a gate at one end and adapted to open, a plurality of ground engaging elements at such end whereby to prevent such end of the hopper from sliding along the ground when its other end is elevated, pivoted elevating supports adjacent the elevatable end, 110 said supports provided with rollers adjacent their lower extremities movable track sections to be engaged thereby, a transverse shaft between the ground engaging elements and the elevating supports, and flexible elements carried thereby and attached to said supports whereby rotation of the shaft moves 115 the supporting members along the tracks from horizontal to vertical positions to elevate one end of the hopper.

3. A burial apparatus comprising a hopper provided with soil engaging elements and composed of a plurality of separable sections, means to secure and retain said sections in operative position with respect to each other; pivoted supports secured to the hopper and means to move the supports to elevate the hopper.

4. A burial apparatus comprising a hopper provided with a ground engaging end, pivoted supports secured to the opposite end, means to move the supports from horizontal to vertical positions, to elevate the rear end of said hopper, and means carried by the supports to predetermine the maximum height of elevation of said end of the hopper.

5. A burial apparatus comprising a hopper provided with a ground engaging end, detachable elevating supports carried by the hopper adjacent the opposite end, a shaft carried by the hopper, means to rotate the same and means whereby the rotation of the shaft will raise or lower the hopper.

25 6. A burial apparatus comprising a hopper provided with a soil engaging end, pivoted elevating supports carried by the hopper adjacent its opposite end, a rotatable shaft carried by the hopper, flexible elements carried by the shaft and attached to said supports whereby rotating the shaft will raise or lower the hopper and means carried by the supports to predetermine the maximum elevation of the hopper.

35 7. A burial apparatus comprising a hopper provided with a soil engaging end, detachable elevating supports carried by the hopper adjacent its opposite end, a removable shaft, carried by the hopper, flexible members carried by the shaft and attached

to the elevating supports, means to rotate the shaft to raise or lower the hopper, and means carried by the hopper shaft to retain the hopper at any desired elevation.

8. The combination with a hopper provided with a soil engaging end, and a plurality of detachable elevating supports carrying rollers at their lower extremities, of an elevated track designed to be placed beneath the hopper in operative position with respect to the rollers, and means to move the supports longitudinally with respect to the track to raise and lower the hopper.

9. A burial apparatus comprising a hopper composed of a plurality of separable sections, means to secure and retain the same in operative position with respect to each other, said hopper having a forward ground engaging end, a plurality of pivoted elevating supports adjacent the rearward end, a removable shaft carried by the hopper, a crank to rotate the shaft, detachable flexible members secured thereto and attached to the elevating supports whereby the rotation of the shaft will raise or lower the rearward end of the hopper, and a ratchet and pawl carried by the shaft and hopper to retain the hopper at any desired elevation.

25 10. A burial apparatus comprising a hopper provided with soil engaging elements and composed of a plurality of separable sections, detachable elevating supports pivotally connected with the hopper, means to move the supports to elevate the hopper, and means to linearly vary the supports for effecting different elevations of one end of the hopper.

JOHN DAWSON JENNINGS.
